US00D804315S

(12) **United States Design Patent** (10) Patent No.: **US D804,315 S**
Galvin et al. (45) Date of Patent: ** Dec. 5, 2017

(54) **BOTTLE**(71) Applicant: **PepsiCo, Inc.**, Purchase, NY (US)(72) Inventors: **Ian Galvin**, Chicago, IL (US);
Raymundo Martinez, Berwyn, IL (US);
Katie Ozamiz, Chicago, IL (US);
Wade Fournier, Chicago, IL (US)(73) Assignee: **PepsiCo, Inc.**, Purchase, NY (US)(**) Term: **15 Years**(21) Appl. No.: **29/582,183**(22) Filed: **Oct. 25, 2016**(51) LOC (10) Cl. **09-01**

(52) U.S. Cl.

(57) **CLAIM**

The ornamental design for a bottle, as shown and described.

DESCRIPTION

FIG. 1 is a top front perspective view of a bottle showing the claimed design;

FIG. 2 is a bottom rear perspective view of a bottle showing the claimed design;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The dashed broken lines in the figures show portions of the bottle that form no part of the claimed design.

The dot-dash broken lines in the figures show boundaries that form no part of the claimed design.

1 Claim, 7 Drawing Sheets
